STRINGED MUSICAL INSTRUMENT

George Barr, New York, N. Y., assignor of one-half to Arthur V. Smith, New York, N. Y.

Application November 19, 1951, Serial No. 17,473

Term of patent 14 years

(Cl. D56—9)

To all whom it may concern:

Be it known that I, George Barr, a citizen of the United States, residing in New York, in the county of New York and the State of New York, have invented a new, original, and ornamental Design for a Stringed Musical Instrument, of which the following is a specification, reference being had to the accompanying drawing, forming a part hereof.

Figure 1 is a top perspective view of a stringed musical instrument showing my new design;

Figure 2 is a front elevation thereof;

Figure 3 is a side elevation of the left-hand end thereof; and

Figure 4 is a side elevation of the right-hand end thereof.

The bottom of the instrument is plain.

I claim:

The ornamental design for a stringed musical instrument, substantially as shown and described.

GEORGE BARR.
